LOOM

Charles L. Kennedy, Columbia, S. C.

Application April 9, 1932, Serial No. 604,303

25 Claims. (Cl. 139—145)

This invention relates to looms and has for its principal object the provision of a simple device for checking the shuttle at the end of its travel so that it comes to rest in exact position and is discharged from such position by a trigger operated spring mechanism the latter cooperating with the binder to release this member just prior to the driving forward of the shuttle.

A further object of the invention lies in the provision of mechanism which constitutes a unit readily attached to the lay beam and adjustable thereon without alteration of such of the mechanism as is retained. By having the mechanism a unit an entirely new mechanism can be applied in about five minutes as against the period of nearly a half hour where a picker stick must be replaced.

A further object of the present invention lies in the provision of a spring driven picker in which the picker has an elongated guide in order that the blow against the shuttle may be given exactly in the axis of the shuttle and in which the adjustment of the spring, the adjustment of the trigger, the adjustment of the timing, the adjustment of the position of the picker spring housing, the positioning of the bumper and the positioning of the link that holds the free end of the binder are each and every one independently adjustable whereby an alteration of relative arrangement of any one or more of the parts will not affect the adjustment of the other parts thereby saving a very appreciable time.

An important feature of the present invention lies in the provision of a spring pressed picker in which the spring is fully expanded at the time the shuttle enters the shuttle box and is compressed while the shuttle is at rest.

A still further object of the invention lies in the provision of a discharge and checking device which is little affected by humidity and which is substantially, if not entirely, free of the fault of knocking off. This knocking off or jarring of the clutch so as to stop the machine is the result of accumulative action which is avoided in the present mechanism by having the binding action directly dependent upon the speed of the shuttle.

A particular object of the present invention is to lengthen the life of the various parts and to cut down by an appreciable percent the amount of power required to drive the loom. These objects are achieved by the elimination of the picker stick and the cam, the latter causing excessive wear on three of the teeth of the counter shaft gear, that is, the three teeth which are

in engagement at the time of the sharp jar when the cam is in discharge position.

Other objects of the present invention will be ascertained by a consideration of the following specification and are particularly set forth in the appended claims.

In practically all previous looms the shuttle is driven by a picker stick which in turn is cam operated. Many attempts have been made, it is true, to drive the shuttle back and forth by magnetic or spring action but as far as I know these devices have not gone into commercial production due in many cases to some very obvious and outstanding disadvantage, for example, in most of the spring discharge shuttle mechanisms either the shuttle will not come to rest in precise position so as to discharge the old bobbin and receive a new one but in fact some of the proposed devices are so arranged that the bobbin must enter and leave at the side of the shuttle and there is no mechanism on the market that can have this action. It is old to use a leather faced binder to check the motion of the shuttle and to hold the shuttle firmly in desired position until it comes to rest and then later to release the pressure on the binder but in none of these devices is such action associated with a spring discharge mechanism. In the present device I have a reciprocating cam to the follower of which a trigger is attached and to the trigger in turn is connected the binder link so that these parts are associated together in correct relationship altho I preserve independent adjustment of all the several parts. The cost of the new mechanisms described herein is appreciably less than half of the cost of the parts which are dispensed with but this is not the principal advantage for the saving in time, which is much more important, is very marked as the same mechanism can be adjusted to discharge and receive light or heavy shuttles and can operate with a shuttle of any of the lengths ordinarily used.

In the drawings:

Figure 1 is a plan view of a portion of a loom showing my device in place.

Figure 2 is an end view, the loom itself being diagrammatically shown for clearness of illustration.

Figure 3 is a front elevation of the check and discharge mechanism which for convenience is hereafter called the gun.

Figure 4 is a plan view of the gun with the shuttle in its bobbin receiving position.

Figure 5 is a similar view after the discharge of the shuttle.

55

Figures 6, 7 and 8 are sectional views thru the gun showing respectively the position of the parts when the shuttle is in the box, when the trigger is cocked and when the shuttle is discharged. Figure 9 is a view showing a modified form of spring which is in fact the preferred form but in the other figures I have shown only one spring for convenience of illustration.

Figure 10 is a horizontal section thru the toggle.

Figures 11 to 15 are sections taken on lines shown in Fig. 6 bearing similar numerals.

Figures 16 and 17 are details illustrating the modified form of toggle.

My device is intended for application to already existing looms as no change is required in the modern loom save the replacement of the usual picker stick mechanism by my present gun which forms with the ordinary binder and the bottom of the lay beam together with the optional cover, not shown in any of the figures, a shuttle box. Inasmuch as the loom itself has nothing to do with the present invention the drawings illustrate the loom in a diagrammatic manner only, 10 being the frame, 11 the crank shaft which, of course, is the usual main drive shaft receiving its power thru a pulley from the line shaft if such be used or from the individual electric motor as is becoming very common. The cranks 15 are pivotally connected to the pitman 16 which is joined as at 17 to the so-called sword 18 pivoted on the transverse rock shaft 20. At their upper ends the two lay swords 18 carry the lay beam 23 which may be entirely of wood 25 but more frequently has metal ends. My device will work equally well with either. At the rear of the lay beam 23 is the reed 25 and the binder 26. The dagger rod mechanism indicated generally by the numeral 27 is of ordinary form and 30 serves to throw out the clutch when the lay beam reaches one end of its stroke without the shuttle being in place in the shuttle box. All of the portions so far are old and well known and I 35 make no claim whatsoever to them save in combination with the new elements which will now be described.

Having particular reference to Figure 4 the binder 26 which moves about its fixed pivot 29 forms the rear side of the shuttle box the front 40 guide portion of which is a smooth piece 30 of hardened steel which may be, if desired, and preferably is, integral with the angle bracket 31 which holds the gun on the lay beam 23. As 45 shown in Figure 3 the downwardly projecting plate 32 of the angle bracket 31 is provided with slots 32a to accommodate the lag screws 32b which construction permits the adjustable mounting already mentioned. The shuttle 33 in Figures 4 and 6 is at the end of its travel in one 50 direction and rests against the picker 34 which latter, as will be seen from the sectional view, is a steel cup containing resilient material 35 preferably a coiled strip of leather. The buffer bumper 38 to the rear of the picker is preferably 55 also a cup-like member also containing a filling such as 39 of leather, likewise for cushioning purposes.

The trigger 70 is connected to the bumper 38 by a rod 41 and a lever 43 pivoted to the gun housing as at 45 is also secured to the trigger 70 at one end and slidably receives at its other end a link 46 pivoted as at 47 to the free end of the binder and passing thru a slot 48 in the centrally pivoted lever 43. Adjustment is provided by means of the lock nuts 49.

Referring now particularly to Figure 6 the barrel 50 of the gun for economic reasons is preferably manufactured from a rather high grade of tubing which can be purchased commercially so smooth as to require no grinding or polishing. This barrel or tube 50 is permanently secured to the guide 30 and/or bracket 31 as by welding or brazing and has its inner end, which is a disk 51, permanently secured to the barrel or tube 50 but I prefer that the other end, the disk or washer 52, shall be replaceably secured in position. This I accomplish by threading the rod 55 into the permanently secured end 51 and by binding the closure disk 52 in place as by the nut 56. The removable disk 52 is of two diameters the lesser diameter fitting very snugly within the bore of the barrel or tube 50 as I desire that this rod 55 shall be exactly coaxial with the tube. The picker sleeve 57 fits rather snugly within the barrel 50 and has an elongated bearing surface 20 which insures that its travel shall be in a line precisely parallel to the axis of the shuttle. The inner bore 58 of the picker sleeve 57 extends thruout the length of the sleeve except at the inner end of which there is an inwardly directed 25 lip 59 serving as a shoulder for the one or more springs 60 which drive the shuttle thru the picker.

Slidably engaging the opening in the annular lip 59 is a spring compressor sleeve 62 permanently and preferably integrally secured to the spring compressor base 63 from which extends the bracket 64, the latter sliding in a slot 65 in the barrel 50 and also in slot 66 in the picker sleeve 57.

The trigger 70 is a flat sheet of metal carrying integrally at its forward end a vertically disposed sleeve 71 which pivotally receives the downturned end 73 of the link 41 which is fast to the bumper bracket 75 in which is adjustably mounted the bumper 38 the correct positioning being secured by means of the lock nuts 76. This bumper bracket has an inwardly extending guiding surface 77 which slides a short distance along the hardened steel guide plate 30. I also prefer that the bumper bracket be held to the gun barrel 50 by some resilient means as for example, the spring 79 having just sufficient tension to hold the bumper bracket guide against the main guide.

In the vertical bearing 71 of the trigger below the bottom of the downturned end 73 is sweated or otherwise secured a stud shaft 80 on which is rotatably mounted the roller 81 which is the cam follower. It will be noted that this cam follower 81 is directly connected to the trigger 70 and consequently to the pivoted lever 43 which in turn is permanently secured to the trigger while the link 41 is not permanently secured but merely has a pivotal connection the intention being that the bumper and its bracket and the link 41 can readily be lifted off of the gun barrel without disturbing any other part, the downturned end 73 being slidable in the trigger bearing.

Adjustably mounted in the bracket 64 of the spring compressor is a short section 85 of rod permanently secured to the cable 90 which extends inwardly toward the relatively large guide pulley 91 carried in a pair of depending ears 92 preferably integral with the gun barrel 50 and then downward, as seen in Figure 3, to the idle pulley 94 (Figure 2) loosely mounted on the rock shaft 29, thence upwardly and rearwardly to its adjustable connection 95 with the tube 96 pivoted as at 97 to the gear 98 on the countershaft 75.

99 which is a transverse shaft parallel to the main drive shaft 11 which is the crank shaft. The pinion 100 fast on the end of the main drive or crank shaft 11 meshes with the gear 98 and drives the countershaft 99 at half speed. The countershaft 99 at its distant end, as seen in Figure 2, carries a crank 102 pivoted to a tube 103 exactly similar to the tube 96 and connected to the opposite shuttle mechanism.

10 The cam 105 is adjustably secured on rod 85 so that this cam which governs the discharge of the trigger 70 can be moved with respect to the adjusting end of the cable 90. The beveled end 106 of the cam first moves the trigger forwardly 15 or toward the operator so as to release the binder 26 and then an instant later releases the trigger.

The toggle mechanism which, while not essential is highly desirable, is shown in section in Figure 10 and serves to increase greatly the speed 20 of action of the trigger. The preferred form is shown in Figure 10 in which the toggle barrel 107 is an integral extension on the gun barrel having a smooth bore therethru in one end of which is threaded the adjusting screw 108 and 25 in the far smooth portion of the bore a small cupped cylindrical slide 109 is held in contact with the connecting pin 110 which rests in an indentation 111 in the body of the trigger 70. Since each of the two ends of this connecting pin 30 110 is in a cup-like cavity and since the plunger slide 109 is constantly urged outward by the spring 112 it is always held in place altho not fastened. Upon first movement of the cam surface 106 against the roller or follower 81 the action 35 is solely to release the toggle mechanism of Figure 10 in order that the binder can be free. The toggle has important action just beyond the position in which the binder is free, namely, as the trigger starts to move forwardly by the cam 40 action the toggle snaps it quickly into extreme release position entirely freeing the sleeve 57 of the picker. The active end of the trigger is recessed as at 114 so as to clear at all times the sleeve of the spring compressor.

45 In Figures 16 and 17 is shown a modified and very satisfactory form of toggle mechanism, this being merely a single piece of wire 117 having a central bight and passing at one end thru a hole 118 in the trigger 70 and passing at its 50 other end thru a hole 119 in a bracket 120 which is brazed or otherwise secured to the barrel 50 of the gun for that purpose. In spite of the extreme simplicity of this modified spring it serves the purpose remarkably well and except for the 55 adjustment of the mechanism shown in Figure 10 the spring 117 gives the same action.

The operation of the device is as follows, beginning with the lay beam in its forward position and the shuttle at the right hand end of its travel. 60 The positions of the parts are as shown in Figures 4 and 6 and the reed has just beaten the last thread against the cloth. The drive shaft is revolving in counterclockwise direction as seen in Figure 2 and the pin 97 on the half time gear 98 65 has just passed dead center. As the drive shaft turns, the countershaft 99 is revolving in clockwise direction and the lay beam is moving rearwardly, that is, toward the warped threads. The cable 99 is now taut and is compressing the spring 70 69. The cam 105 is consequently advancing inwardly toward the cam roller 81 but no other action is taking place. As the beam reaches almost its mid-position in its rearward oscillation the cam strikes the roller and causes the trigger 75 10 to move forward a slight amount but not

enough to free the plunger. This movement, however, does accomplish an important mission, it turns the lever 43 about its pivot 45 and frees the link 46 which is secured to the free end of the binder which latter is therefore free to turn 5 about its pivot 47 and therefore offers no appreciable friction to the shuttle.

An extremely slight further movement of the drive shaft brings the lay beam into line with the center of the shed and at this moment the 10 cam releases the trigger 70 which under the urge of the toggle spring 112 or 117 snaps the trigger rapidly to release position, freeing the picker sleeve or plunger and discharging the shuttle with a powerful throw which it will be noted is in 15 direct line with the axis of the shuttle.

Instantly after the shuttle has been discharged the parts are in the positions shown in Figures 5 and 8. No bumper at this end is needed for the plunger and the picker which is carried thereby 20 because the plunger spring is secured relatively permanently to the two sleeves, that is, the plunger sleeve and the spring compressor sleeve. The picker is consequently spring held against forward and backward movement. At this time 25 the bumper bracket which adjustably carries the bumper has slid along the smooth face of the shuttle guide 30 to the inward end of its movement which, however, is very slight. The relatively light spring 68 is acting at this time to 30 keep the slack out of the cable and the bumper bracket spring 79 holds the bumper bracket firmly against the face of the guide. It might be remarked here that the principal function of this spring is to prevent noise and to obviate back- 35 lash. The spring is so constructed as to render convenient the lifting off of the unit consisting of the trigger 40, the lever 43 and the link 41, the latter carrying the bumper and its bracket.

Still further movement of the drive shaft carries the lay beam to its extreme rear position without any change in the mechanism of the shuttle actuating device. Upon forward movement of the lay beam the spring 68 causes the return of the shuttle compressor sleeve 62 and 45 this latter carries with it the plunger or picker sleeve 57 because the spring 60 is so much stronger than the spring 68. The cam 105 is also moving outwardly or toward the end of the lay beam under the urge of the spring 68 and this movement of the parts within the barrel 50 continues until the lay beam is again at its extreme forward position. At this time the lay beam starts its return or rearward movement, the shuttle box at the right being still empty. At such time as 55 the lay beam is approaching central position the pulling on the cable is entirely released and the spring 68 has returned all of the parts almost to initial position.

The binder, however, is still loose and the 60 bumper while in engagement with the picker rear is not at the outward limit of its travel nor is the trigger in holding position, on the contrary being held outward to the full limit of the trigger travel by the toggle link 110. The parts are in exactly 65 this position as the shuttle moves from the free end toward the end under consideration. The shuttle enters the shuttle box being guided, if necessary, by the somewhat beveled inner end 121 of the shuttle guide plate 30 and passes freely 70 into the shuttle box until the flat side of the shuttle engages the leather face of the binder, this engagement being possible by the presence of the usual spring between the rear face of the binder and the dagger rod clip. A slight fric- 75

tion is therefore exerted on the shuttle as it moves toward the end of its stroke.

As the pointed end of the shuttle strikes the counter-sunk leather 35 in the pocket 34 it causes a rearward movement of the picker and the bumper 38 which at this time is in contact with it. This engagement moves the plunger 57 outward just sufficiently to clear the trigger 70 which because of the rearward movement of the bumper bracket 75 and the pivotal engagement of the link 41 with the trigger, turns the lever 43 sharply about its pivot under the snap action of the toggle, snapping the trigger into closed or retaining position and simultaneously snapping the binder against the shuttle with a pressure dependent upon the speed of the shuttle. The shuttle therefore is held in a viselike grip and remains stationary at the end of its travel without rebound. This completes the cycle which is 20 repeated as before.

It will be noted that the entire gun device is a single unit which may be secured to the lay beam by the usual two guide screws 32b shown in Fig. 3 and upon removal of these two screws 25 the entire device can be released as a unit since the downturned end 47 of the link 46 is loosely received in the leather loop 123 which lies between the dagger rod clip and the free end of the binder. For extreme convenience of dismantling the unit I prefer to unfasten the connection between the cable and the crank tube 96 or 103 on the countershaft 99 but where time is not so important I prefer to retain the cable on the loom and to disconnect the cam and the 30 lock nuts which secure the cable to the spring compressor bracket 64. These lock nuts just mentioned provide for the proper tension on the spring and provide a heavier or lighter throw. It will be noted that this adjustment is entirely 35 independent of the adjustment of the cam on the cable and consequently a tightening or a loosening of the spring tension will not alter the timing which is controlled by the position of the cam alone because the crank pin 97 is arranged 40 on the half time gear in correct position and is not sensitive as to time as is the cam of the usual picker stick action. The wear on the teeth is substantially uniform because of the smooth action of the device whereas in the cam operated picker stick the wear is concentrated on 45 three of the teeth.

What I claim is:

1. In a shuttle mechanism, a picker, a spring for driving the picker, a trigger for releasing the picker and, shuttle check mechanism and means for releasing the shuttle check mechanism prior to release of the picker.
2. In a shuttle mechanism, a spring pressed picker, a trigger for releasing the picker, a binder, means for connecting the binder to the trigger to draw the binder against the shuttle as the shuttle reaches the end of its travel and means for releasing the binder prior to movement of the trigger to discharge the picker.
3. In a shuttle operating mechanism for looms, a spring actuated picker, a trigger for releasing the picker and a toggle spring for holding the trigger in released and in holding position.
4. In a shuttle actuating mechanism for looms, a spring pressed picker, a bumper, means connecting the trigger and the bumper, and toggle means for giving a snap action to the connecting means to throw the trigger into and out of position.
5. In combination, a picker, a spring for actuating the picker, a trigger for holding the picker

retracted against the action of said spring, means for discharging the trigger, a bumper, means connecting the bumper and the trigger, a pivoted lever connected to the trigger, a link connected to one end of the lever and adapted to be connected at the other end to the free end of the binder, and a single housing carrying all of the parts mentioned except the binder, and means for detachably securing said housing to the lay beam of the loom whereby all of the mechanism for discharging and receiving the shuttle may be quickly detached from the loom when damaged and be replaced as a unit by similar mechanism.

6. In a shuttle discharge mechanism, a cylinder, an elongated open-ended hollow plunger slidable 15 in said cylinder, and a picker rigidly secured to said plunger, a piston normally within said plunger, a spring between said piston and the plunger head, and means for moving the piston axially of the cylinder to thereby actuate said plunger. 20

7. In a device of the character described, a hollow plunger, a picker carried by said plunger, a spring within the hollow of the plunger, a sleeve within the spring, an annular stop extending inwardly on the plunger, an annular stop extending outwardly from the sleeve, means for moving the sleeve with respect to the plunger to compress the spring between the two annular stops, said inwardly extending annular member snugly engaging the sleeve and said outwardly 30 extending annular member snugly engaging the plunger whereby as the parts move with relation to each other they are guided by spaced bearings.

8. In a discharge mechanism for looms, a rod, a 35 sleeve slidable on said rod and having at one end an annular shoulder, a sleeve having two bores, the smaller bore fitting said first mentioned sleeve and the larger bore fitting the shoulder, spring means between the two sleeves, a picker carried 40 by one of said sleeves, means for moving the sleeves with respect to each other to compress the spring and means for releasing the spring to cause the picker to discharge a shuttle.

9. In a shuttle operating mechanism for looms, 45 a spring pressed picker, a trigger for holding the picker against spring pressure, shuttle actuated means for moving the trigger to holding position, cam means for operating the trigger from holding position, a cable connected to the cam to reciprocate the latter, and means for separately adjusting the cable and the cam with respect to the trigger.

10. In a device of the character described, a pair of coaxial sleeves each having a stop member 55 at one end thereof, a spring inside of one sleeve and outside of the other and positioned against said stops, a trigger for holding one of the sleeves, and means for making the other sleeve to compress the spring while the one sleeve is held 60 by said trigger.

11. In a shuttle discharging mechanism for looms which is removable as a unit from the loom, a cylinder, a plunger within said cylinder, a picker fast to said plunger, spring means for 65 operating said plunger, a trigger, shuttle actuated means for moving the trigger to plunger holding position, trigger release mechanism, and cable means for compressing said spring while the trigger is in holding position.

12. In combination, a trigger for a spring 70 pressed picker, a pivoted binder, a link secured to the free end of the binder, and a lever pivoted intermediate its ends on an axis parallel to and at a fixed distance from the binder axis, one end 75

of said lever being secured to said trigger and the other end of said lever being secured to the free end of the binder by means of said link.

13. In a spring discharge shuttle mechanism for looms of the type having a shuttle and a shuttle box, a spring pressed picker, releasing means for discharging the picker, means for compressing the spring and mechanism so timed as to start the compressing of the spring after the shuttle has reached home in the shuttle box.

14. In a loom, a lay beam, a shuttle, a picker, a spring for driving said picker, release mechanism for discharging a picker, a bumper, means connecting the bumper and the trigger to set the trigger upon coming to rest of the shuttle, a reciprocating cam for releasing the trigger to discharge the shuttle, a toggle mechanism for holding the trigger in discharge or in release position whereby when it is desired to shake the reed 20 of the loom to straighten the warp threads the shuttle need not be taken from its place but the trigger can be released by hand against the action of the toggle mechanism to prevent compression of the spring.

15. In combination, a lay beam, a shuttle guide adapted to be detachably secured to said lay beam, a gun barrel secured to said guide, a plunger slidably mounted within the cylinder, a spring compressor slidably mounted within said plunger, a stop on the plunger, a stop on the compressor, spring means between the compressor and the plunger, a central rod on which the compressor is slidably mounted, a spring mounted on said rod to urge the spring compressor to the outer 30 end of the gun barrel, a trigger carried by the barrel for holding the plunger against the urge of its spring, a cable adjustably secured to the spring compressor, a cam adjustably secured to said cable, and a cam follower carried by the trigger and lying in the path of said cam to release the trigger to discharge the plunger.

16. In combination, a cylinder, a spring pressed plunger within said cylinder, a trigger for holding the plunger, means for releasing the trigger, a spring pressed toggle link for snapping the trigger into plunger holding position and into plunger releasing position, a bumper lying to one side of the cylinder and connected to said trigger whereby when the bumper is struck the trigger will be thrown against the action of the spring toggle into plunger holding position, a lever pivoted to said cylinder centrally at its two ends, one of the ends of said lever being pivoted to the trigger, a pivoted binder adapted to check the shuttle as 50 it reaches the end of its travel, and a link connecting the free ends of the binder and the lever.

17. In a loom structure, a lay beam, means for oscillating the lay beam, a spring pressed picker mounted at one end of said lay beam, means for compressing said spring, means for discharging said spring, said means being so timed that the picker is discharged when the lay beam is at the center of its stroke and whereby compression of said spring begins after the shuttle has reached 60 the end of its travel against the picker.

18. A shuttle actuating unit for looms of the type having shuttle boxes at the ends of the lay beam in which one side of each box consists of a

binder, said unit comprising a cylinder support adapted to be secured to the lay in a manner to form the opposite side of the shuttle box, a cylinder on said support, a spring actuated plunger in said cylinder, a picker secured to said plunger, a second plunger for compressing said spring against the first, a trigger for holding said first plunger during compression, a cam secured to said second plunger for releasing said trigger, means for linking the trigger to said binder 10 whereby movement of the trigger releases the binder, and means located in the path of the shuttle and linked to the trigger for setting the trigger and thereby moving the binder to holding position.

19. In a unitary picker mechanism, a picker, a spring for driving the picker, a trigger for releasing the picker and shuttle check mechanism linked to the trigger to operate the same to 15 picker holding position.

20. The device of claim 19 in which linkage is provided for connecting said trigger to a loom binder whereby releasing the trigger moves the binder to open position and setting the trigger moves the binder to shuttle holding position.

21. In a picker mechanism, a shuttle box, comprising a binder on one side, said binder being pivoted at one end, a link on the other end of the binder, a lever pivoted intermediate its ends and adjacent said binder, one end of the lever 30 connected to said link, a second link pivotally supported on the other end of the lever and a bumper supported on the free end of said second link whereby the impact of a shuttle against the bumper operates the binder to shuttle binding 35 position.

22. The device of claim 21 in which means are provided for acting on said lever to move the binder from shuttle engaging position.

23. In combination in a shuttle box for looms, 40 a binder for braking and stopping the shuttle, a picker for receiving and throwing the shuttle, said binder being normally set to allow the shuttle to pass into the box sufficiently far to strike said picker, means actuated by the impact of the 45 shuttle on the picker for operating the binder to grip and stop the shuttle whereby there is no rebound, and a latch provided to lock the picker in throwing position, said latch being connected to said impact actuated means whereby the locking of the picker is caused by said impact on the shuttle.

24. The device of claim 23 in which means is provided for connecting the latch to the binder whereby releasing the latch releases the binder. 55

25. In a high speed loom having an oscillating lay beam, a shaft for oscillating the beam, a unitary shuttle throwing and receiving device secured to each end of the beam, each device comprising a spring actuated picker, means individual 60 to each picker for storing shuttle throwing energy in the picker spring, each of said means including a cable, a crank shaft driven from the first mentioned shaft, and means on said crank shaft for operating said cables alternately whereby 65 either unitary device may be adjusted or replaced entirely independent of the other unit.

CHAS. L. KENNEDY.

CERTIFICATE OF CORRECTION.

Patent No. 2,065,076.

December 22, 1936

CHARLES L. KENNEDY.

It is hereby certified that error appears in the printed specification of the above numbered patent requiring correction as follows: Page 4, first column, line 55, claim 1, strike out the word "and"; and that the said Letters Patent should be read with this correction therein that the same may conform to the record of the case in the Patent Office.

Signed and sealed this 16th day of March. A. D. 1937

(Seal)

Henry Van Arsdale
Acting Commissioner of Patents.
